RECEPTACLE CAPPING APPARATUS

Irwin Kotcher, Brooklyn, N. Y.

Application July 23, 1943, Serial No. 495,957

8 Claims. (Cl. 226—92)

This invention relates to a receptacle capping device, mainly designed for applying caps to cartons which have been previously filled, the general object of the invention being to provide an elevator for lifting a group of cartons from a conveyor into capping position, mechanical and pneumatic means for removing caps from holders and placing the caps over openings in the cartons and plunger means for pressing the caps into the openings of the cartons.

The present invention is an improvement over that forming the subject matter of application filed by me on May 19, 1937, Serial No. 143,583, which has matured into Patent No. 2,167,894, dated August 1, 1939.

The invention is illustrated in the accompanying drawings in which:

Figure 1 is an elevational view of the invention. Figure 2 is a section on the line 2—2 of Figure 1. Figure 3 is a section on the line 3—3 of Figure 1. Figure 4 is a section on the line 4—4 of Figure 1. Figure 5 is a section on the line 5—5 of Figure 1. Figure 6 is a section on the line 6—6 of Figure 5. Figure 7 is a section on the line 7—7 of Figure 1. Figure 8 is a section on the line 8—8 of Figure 6. Figure 9 is a section on the line 9—9 of Figure 6. Figure 10 is a section on the line 10—10 of Figure 3.

Figure 11 is a section on the line 11—11 of Figure 4.

Figure 12 is a section on the line 13—13 of Figure 4.

Figure 13 is a view of the fingered member for stopping movement of the cartons by the conveyor at the rear end of the elevator.

In these drawings, the letter A indicates a supporting frame adjustably connected as at a to the foot portions A'. The frame carries the front and rear grooved rollers 1 for the horizontal conveyor 2 which is composed of a plurality of endless coiled springs which are spaced apart and fit in the grooves. One of these rollers can be driven in any suitable manner, though in actual practice the conveyor will receive cartons C from a filling apparatus and the conveyor can be driven from this filling apparatus. The upper reach of the conveyor passes over a horizontally arranged inverted channel-shaped member 3 forming a part of the frame and which is provided with slots extending longitudinally. An elevator E, composed of a plurality of elongated longitudinally extending plates 4 spaced apart and connected with a base 5 is supported for vertical movement in the frame and its plates are adapted to pass through the slots of the member 3 and between

the springs of the conveyor 2. This elevator is adapted to lift the cartons off the conveyor into cap receiving positions and then after the caps have been applied the elevator is lowered to replace the cartons upon the conveyor. Horizontally arranged longitudinally extending guide bars 6 are suitably supported by the frame, one on each side of the conveyor for holding and guiding the cartons as they are being moved by the conveyor and also while they are being moved by the elevator. Vertically extending rods 7 have their upper ends attached to the elevator; these rods being arranged in pairs with a pair connected to each end portion of the elevator, the rods being preferably of non-circular shape in cross section and pass through similar shaped holes in cross bars 8 at the lower part of the frame and springs 9 connect the lower portions of the rods to the bars 8 to normally hold the elevator in lowered position. The lower ends of the rods of each pair are connected together by the cross pieces in which engage the outer ends of a pair of levers 11 pivoted intermediate their ends to parts of the frame as shown at 12 and a yoke 13 is pivoted to a part of the frame as shown at 14 and has its free end resting upon the inner ends of the levers 11 and said inner end carries a roller 15 engaged by a cam 16 on a horizontal shaft 17 suitably journaled in the lower part of the frame and rotated in any suitable manner. Thus when the inner ends of the levers are moved downwardly by engagement of the rollers 15 by the cam 16 the outer ends of the levers will lift the rods 7 and thus raise the elevator; the springs 9 returning the elevator to lowered position. The cam, of course, is so formed as to hold the elevator in raised position long enough for the capping operation to be performed and then the elevator moves downwardly to replace the cartons upon the conveyor.

In order to prevent the foremost carton of the group of cartons from moving with the conveyor beyond capping position I provide a vertically movable member 18, see Figure 13, which is formed with a plurality of upright fingers 19 for passing through the slots in the channel member 3 and between the springs of the conveyor 2; said member 18 being formed with a shank 20 having a roller 21 at its lower end which rides on a cam 22 on the shaft 17, the shank being guided by the guiding means 23 carried by the frame. The cam 22 is so formed that member 18 will be in raised position extending across the path of movement of the cartons while the elevator is in lowered position so as to permit a group of cartons to be

moved by the conveyor over the elevator and thus preventing the cartons from being moved by the conveyor beyond capping position. Then as the elevator moves downwardly to replace the capped cartons upon the conveyor member 13 is permitted by the cam 22 to be lowered by the spring 24 so that as the cartons are replaced on the conveyor they can move with the conveyor out of capping position.

A longitudinally extending substantially inverted channel member 25 is supported in horizontal position in an upper portion of the frame, this member having its depending flanges with inner faces 26 which slope upwardly and inwardly with the upper edges of these faces merging into short, vertical walls 27, see Figure 7, said vertical walls forming a space for snugly receiving the upper ends of the cartons for holding the cartons against movement, the sloping faces or walls 36 acting to guide the upper ends of the cartons between the vertical walls 27. The member 25 carries a plurality of short vertically arranged tubular members 28 which open out into the space formed by the walls 26 and 27 and each tubular member at one side thereof is formed with an opening 29 for the passage of a cap into the tubular member, the bottom wall of the opening 29 being flush with the top of the member 25.

A plurality of plunger cylinders 30 have their lower ends threaded into holes in the member 25 and each cylinder has a rod 31 passing therethrough, each rod having a head 32 at its upper end which acts as a stop for limiting downward movement of the rod by engaging the upper end of the cylinder and a spring 33 is located in each cylinder and has its upper end bearing against the top of the cylinder and its lower end against a collar 34 on the rod for holding the rod in its lowered position with its lower end extending into the space formed by the channel member 25. Thus these plungers tend to force the cartons downwardly out of the space formed by the channel member 25. A plunger is shown in detail in Figure 10.

The caps C' come in tubular containers 35 and these containers are placed in vertically arranged tubes 36 arranged in a longitudinally extending row on a supporting member 37 at the rear upper portion of the frame. A spring actuated latch 38 carried by the upper part of each tube 36 prevents the container 35 from being accidentally pulled from the tube, see Figures 4 and 7. The upper end of each tube curves downwardly from its rear portion to its front portion as shown at 39 and the rear portion is provided with a vertical slot 40, this top portion of each tube extending beyond the upper end of a container 35.

Horizontally arranged guide bars 41 extend rearwardly from the top part of the frame and at their rear ends are connected together by the cross bar 42 and at the rear ends each bar 41 carries a cam projection 43 which extends upwardly as shown in Figure 7. Slides 44 are supported by the bars 41 and a tubular member 45 has its ends reduced and rotatably supported in lugs 44' of the slides 44. An arm 46 has one end rigidly connected to each end of the tubular member 45 and the other end of each arm carries a roller 47 for engaging the upper edge of a bar 41 and the cam 43, the roller engaging the cam when a slide nears the outer end of its stroke. A spring 48 tends to hold each arm in lowered position. A plurality of tubular arms 49 extend forwardly from the tubular member 45 and are in communication therewith and a cup 50 is attached to the

forward end of each arm 49. Each cup has a perforated rubber gasket 51 attached to its open end, as shown in Figure 7, and as shown in this figure when the slides 44 approach the rear ends of their strokes the rollers 47 will engage the cams 43 so that the tubular member 45 is partly rotated in a clockwise direction which throws the arms 49 downwardly to place the cups 50 in the upper ends of the tubes 36 and thus a cup will pick up a cap C' from a container 35 due to suction occurring in the tubular parts and the cup as will be hereinafter described. Then the slides with the member 45 and the parts carried thereby are moved forwardly to place the cups 50 with the caps carried thereby in the tubular members 28 so that the caps can be pressed into the openings in the upper ends of the cartons C. As will be seen, as the slides 44 move forwardly the rollers 47 will move off the cams 43, thus permitting the springs 48 to lower the arms 46 to place the rollers 47 on the bars 41 and to raise the arms 49 so that the cups will enter the tubular members 28.

The means for reciprocating the slides 44 and member 45 include a pair of levers 52 connected together by a bar 53 and pivoted at their lower ends to brackets 54 attached to a lower part of the supporting frame. A link 55 connects the upper end of each lever 52 to the member 45, as shown in Figure 3 and springs 56 connected with the levers 52 and a part of the frame tend to hold the slides in their rearward positions, shown in Figure 7. Bars 58 are slidably supported in horizontal position by the horizontal guides 59 and each bar 58 has a forked outer end, the prongs of which fit over a lower portion of each lever 52 and the inner end of each bar 58 engages the upper end of a lever 60 the lower end of which is pivoted to a bracket 61. The upper end of each lever 60 carries a laterally extending pintle for a roller 62 engaged by a cam 63, these cams being carried by the shaft 17. The guides 59 have their outer ends of forked construction, as shown in Figure 5 for receiving portions of the levers 52 when the same are moved inwardly by the springs 56 when low parts of the cams 63 are engaging the rollers 62. Thus under the action of the springs 56 and cams 63 the levers 52 are oscillated to reciprocate the slides 44 and the tubular member 45 and the parts carried thereby so as to move caps C' from tubes 36 into capping position in the tubular members 28, and then to return the parts to pick-up position as shown in Figure 7.

The capping plungers 64 depend from a bar 65 and said plungers pass through guiding bosses 66 extending upwardly from a cross member 67 at the top of the supporting frame. Each plunger is provided with a head 68 at its lower end for fitting in a cap C' and for forcing the cap into a hole in the upper end of a carton C. This bar 65 is supported by the cross pieces 69 and each cross piece 69 is connected to the upper ends of a pair of vertically arranged bars 70. The four bars 70 are guided in the frame for vertical movement and are normally held in lowered position by the springs 71 and, as shown in Figure 9, each pair of bars 70 carries a lower cross bar 72 which carries a roller 73, said rollers being engaged by cams 74 on the shaft 17, these cams 74 raising and lowering the capping plungers 64 in conjunction with the springs 71, the parts acting to lower the plungers 64 after the caps C' have been deposited in the tubular parts 28.

In order to prevent damage to the suction cups

and the parts attached thereto by accidental downward movement of the capping plungers I provide angle arms 75 on the links 55 to support the stop members 16 which are located between the bar 65 and the member 67. Thus these members 16 are moved from under the bar 65 when the links 55 move rearwardly so that the bar 65 with the capping plungers can move downwardly but if, for any reason, the levers 52 and links 55 were not moved then the members 16 will prevent the bar 65 from moving downwardly.

A manifold 17 is connected with the tubular member 45 and a flexible conduit 78 connects the manifold to a valve 79; see Figure 8, which is connected by a conduit 80 to a vacuum or suction producing device. An inlet conduit 81 is connected with the conduit 78 in front of the valve 79 and contains a valve 82. These valves 79 and 82 are normally held closed in any suitable manner and they are adapted to be moved to open position by the pivoted arms 83. Each arm has a roller 84 at its upper end for engagement by the cam 22 which actuates the stop member 18 and this cam is so formed that as the arms 43 of the tubular member 45 drop into the tubes 36 the arm 83 of valve 79 will open said valve while the valve 82 remains closed. Thus a vacuum or suction will be produced in the cups 59 so that these cups will pick up the uppermost carton caps in the containers 35 and the valve 79 remains open while the caps are being conveyed into the tubular parts 28. Then when the cups with the caps thereon enter the tubular parts 28 the cam 22 will permit the valve 79 to close and will open the valve 82 so that the suction or vacuum in the cups 59 is broken by air entering through the conduit 81 into the conduit 87 and thus into the cups. This causes the caps to drop from the cups and then the cup carrying parts move back to the position shown in Figure 7 and then the valve 82 is permitted to close and the valve 79 is again opened to create a suction in the cups. Of course, that part of the conduit 78 connected with the valve 79 is not flexible but a sufficient part of the conduit should be made flexible so as to not interfere with the sliding movement of the member 45 and the parts associated therewith.

Pistons 85 are arranged in the containers 38 for raising the caps C' as caps are removed from the upper ends thereof. The rods 86 of the pistons pass through the lower ends of the members 35 and the tubes 36 and are suitably supported for vertical movement. The lower ends of these rods are connected to an angle bar 87 which has its reduced ends 88 engaging guiding grooves in the upright bars 89 forming part of the supporting frame. A vertically arranged rack bar has its lower end connected to the central part of the bar 87 and this rack bar operates in the guideway 91 attached to the front face of the member 37 and a holding dog 92 is pivoted to the lower part of the guideway 91 and engages the rack bar under the action of gravity as shown in Figures 4 and 12. A vertically movable bar 93 has right angularly extending ears 94 at its upper end between which is pivoted a dog 95 as shown in Figures 4 and 11, this dog being adapted to engage the teeth of the rack bar. This bar 93 is guided for vertical movement by the guiding means 96 and is normally held in lowered position by a spring 97 and it is located in rear of an upright 98 formed with a slot 99; see Figure 11. A substantially U-shaped member 100 is provided with a lug 101; see Figures 4 and 6, a portion of

which passes through the slot 99 whereby the U-shaped member is supported for sliding movement on the upright 98 and the upper ends of the limbs of the U-shaped member are curved upwardly and rearwardly to provide the horns 102 for lifting the holding dog 92 into unoperated position when the U-shaped member is lifted. A block 103 is provided at the lower end of the U-shaped member which has a cam part, see Figure 4, for engaging the dog 95 when the U-shaped member is moved upwardly, to move said dog 95 into unoperated position. This member 100 is raised to move the two dogs 92 and 95 into inoperative position by means of a lever 104 and a link rod which connects the lever with a part of the U-shaped member, see Figure 11. The bar 93 is raised by means of a short lever 106 pivoted intermediate its ends to a depending part of the frame with its free end passing into the guiding means 96 under the lower end of the bar and the other end of the lever 106 is connected by a link 107, adjustable as to its length, to a lever 108 pivoted to a part of the frame as at 109 and said lever 108 is engaged by a roller 110 carried by the cam 16 as shown in Figures 4, 5 and 6. Thus once every revolution of shaft 17 roller 110 on cam 16 will engage the lever 108 and thus cause the short lever 106 to raise bar 93 to cause the dog 95 to raise the rack bar 87 which, in turn, raises the member 87 to raise the pistons 85 and thus the caps C' are kept at the upper ends of the containers where they can be picked up by the suction cups. When it is desired to lower the bar the lever 104 is pulled upwardly which through means of the links 105 will raise the U-shaped member 100 to release the dogs and this will permit the piston carrying parts to lower so that a new supply of caps can be placed in the tubes 36.

In order to prevent the rollers 73 carried by the bars 70 from engaging the low parts of the cams 74 cross pieces 10' are carried by lower parts of the main frame and act as stops for limiting downward movement of the bars 70, as shown in Figures 6 and 9.

Thus a group of cartons are brought over the elevator by the conveyor and the first carton of the group is prevented from moving beyond the elevator by the stop member 18 being lifted by the cam 22 on shaft 17 and then the group of cartons is lifted by the elevator until their tops enter the space formed by the flanges of the member 23, the elevator being raised by the cam 16, lever 11 and the rods 7. Caps C' are conveyed from the containers in tubes 36 by the slides 44 and the tubular member 45 and the parts attached thereto to the tubular parts 28 and then the slides return to pick up another group of caps. The caps are pushed into the cartons by the plungers 64 actuated by the upright rods 70 and the cams 74, the cams 74 acting to raise the plungers and the springs 71 acting to move the plungers downwardly to press the caps into the holes of the cartons. Then the plungers are raised by the cams 74 and the elevator is moved downwardly to replace the capped cartons back upon the conveyor and before this happens the stop member 18 is lowered so that the conveyor can move the cartons from over the elevator. Then a new group of cartons is moved by the conveyor over the elevator so that this new group of cartons can be capped. Of course, the cams are so arranged and constructed as to perform the various operations in proper sequence, the cam 22 controlling the

suction to the cups 50 and the roller 110 on cam 16 feeding the caps upwardly so that they can be picked up by the cups 50, the cams 63 reciprocating the cap pick up means by means of the levers 52 and links 55, the springs 56 turning the pick up means to rearmost position. The spring plungers in the housings 30 act to prevent the cartons from sticking in the member 25.

Having described the invention, what is 10 claimed as new is:

1. In a receptacle capping machine, a supporting frame, a conveyor for bringing the receptacles into capping position, a stop member supported for vertical movement in the frame and when raised preventing movement of the receptacles by the conveyor, beyond capping position, an elevator for raising the receptacles off the conveyor, a member in the upper portion of the frame for receiving the upper ends of the receptacles when raised by the elevator, a horizontally movable carriage, cap supporting means, plungers for forcing the caps into the receptacles, a shaft journaled in the frame, cams on the shaft, means actuated by the cams for operating the elevator, the stop member, the carriage and the plungers, suction means carried by the carriage for picking up the caps from the cap supporting means and holding the caps while the carriage is being moved to depositing position after which the suction means are rendered inactive, a conduit connected with the suction means of the carriage and adapted to be connected with a source of suction, valve means in the conduit, and one of the cams of the shaft actuating the valve means.

2. In a receptacle capping machine, a supporting frame, a conveyor for bringing the receptacles into capping position, a stop member supported for vertical movement in the frame and when raised preventing movement of the receptacles by the conveyor, beyond capping position, an elevator for raising the receptacles off the conveyor, a member in the upper portion of the frame for receiving the upper ends of the receptacles when raised by the elevator, a horizontally movable carriage, cap supporting means, plungers for forcing the caps into the receptacles, a shaft journaled in the frame, cams on the shaft, means actuated by the cams for operating the elevator, the stop member, the carriage and the plungers, suction means carried by the carriage for picking up the caps from the cap supporting means and holding the caps while the carriage is being moved to depositing position after which the suction means are rendered inactive, a conduit connected with the suction means of the carriage, valve means in the conduit, and one of the cams of the shaft actuating the valve means, said cap supporting means including tubular members, means for feeding the caps upwardly in said tubular members and means for operating the feeding means from one of the cams.

3. In a carton capping machine, a supporting frame, an inverted channel member supported in the upper part of the frame, the flanges of which have upwardly and inwardly sloping walls terminating at their upper ends in vertical walls for receiving the upper end of a carton, a tubular member extending upwardly from the channel member and in communication with a portion of the space formed by the flanges of said channel member, a horizontally movable

carriage supported by the frame, a tubular member supported for rocking movement in the carriage, a tubular arm extending forwardly from the tubular member, a suction cup carried by the forward end of the arm, a vertically arranged tubular member for receiving caps, cam means for tilting the first-mentioned tubular member to place the cup in position to pick up a cap when the carriage is in its rearward position, the cup depositing the cap in the tubular member of the channel member when the carriage is in its forward position, a conduit connected with the tubular member of the carriage and adapted to be connected with a source of suction, valve means in the conduit normally closing the conduit, other valve means for connecting the conduit with the atmosphere, a cam for opening the first valve means and closing the second valve means when the carriage is in 20 is rearward position and while the carriage is traveling to its forward position, after which the cam closes the first valve means and opens the second valve means to cause the cup to release the cap to place the cap in the tubular member of the channel member, a plunger for forcing the cap into the carton, an elevator for raising and lowering the carton, means for actuating the elevator, means for actuating the carriage and means for actuating the plunger, said 30 means including a single shaft on which the cam for operating the valve means is arranged.

4. In a carton capping machine, a supporting frame, an inverted channel member, the flanges of which form a space for receiving upper ends of 35 cartons, said member having openings vertically arranged therein, means for feeding caps into said openings, a plurality of vertically movable plungers carried by the frame, a bar to which the upper ends of the plungers are connected, members depending from the bar, spring means 40 connected to said members for moving them and the bar downwardly to cause the plungers to force the caps into the cartons, and cam means for raising the members against the action of the 45 spring means.

5. In a carton capping machine, a supporting frame, an inverted channel member, the flanges of which form a space for receiving upper ends of 50 cartons, said member having openings vertically arranged therein, means for feeding caps into said openings, a plurality of vertically movable plungers carried by the frame, a bar to which the upper ends of the plungers are connected, members depending from the bar, spring means 55 connected to said members for moving them and the bar downwardly to cause the plungers to force the caps into the cartons, and cam means for raising the members against the action of the spring means, and spring plungers for forcing 60 the cartons from out of the space formed by the channel member.

6. In a carton capping machine, a supporting frame, a horizontally movable carriage supported by the frame, capping means in the frame, 65 vertically arranged cap containers supported by the frame in rear of the capping means, a tubular member supported for rocking movement in the carriage, tubular arms extending forwardly from the tubular member, a suction cup at the forward end of each arm, arms extending rearwardly from the tubular member, spring means connected with the last-mentioned arms for holding the tubular arms in raised position, cam means engaging the second-mentioned arms at 70 the rear end of the stroke of the carriage for

tilting the tubular member to place the cups in the cap containers, means for reciprocating the carriage, the cups placing the caps in capping position at the end of the forward stroke of the carriage, a conduit connected with the tubular member and adapted to be connected with a source of suction, a valve normally closed in the conduit, a pipe connecting the conduit in front of the valve with the atmosphere, a normally closed valve in said pipe, means for opening the first-mentioned valve when the cups are in the cap containers and while the carriage is moving forwardly, said means opening the second valve when the carriage reaches its forward position to break the suction in the cups.

7. In a carton capping machine, a supporting frame, a horizontally movable carriage supported by the frame, capping means in the frame, vertically arranged cap containers supported by the frame in rear of the capping means, a tubular member supported for rocking movement in the carriage, tubular arms extending forwardly from the tubular member, a suction cup at the forward end of each arm, arms extending rearwardly from the tubular member, spring means connected with the last-mentioned arms for holding the tubular arms in raised position, cam means engaging the second-mentioned arms at the rear end of the stroke of the carriage for tilting the tubular member to place the cups in the cap containers, means for reciprocating the carriage, the cups placing the caps in capping position at the end of the forward stroke of the carriage, a conduit connected with the tubular member and adapted to be connected with a

source of suction, a valve normally closed in the conduit, a pipe connecting the conduit in front of the valve with the atmosphere, a normally closed valve in said pipe, means for opening the first-mentioned valve when the cups are in the cap containers and while the carriage is moving forwardly, said means opening the second valve when the carriage reaches its forward position to break the suction in the cups, a piston in each 10 container for moving the cups upwardly therein, a rack bar, means for connecting the rack bar with the pistons, a dog, a member carrying the dog, means for reciprocating the dog carrying member, a holding dog for the rack bar and 15 manually operated means for moving the dogs to releasing position.

8. In a carton capping machine, a supporting frame, a member in the upper portion thereof, for receiving the upper ends of cartons to be capped, cap containers supported in the frame, a horizontally movable carriage, means carried by the carriage for conveying caps from the containers to the member, vertically arranged levers, links connecting the upper ends of the levers to the carriage, spring means connected with the levers for holding the carriage in its rearward position, cam means for moving the levers outwardly to move the carriage to its forward position, means for raising and lowering the cartons, plungers for forcing the caps into the cartons, means for actuating the plungers, and means carried by the links for preventing downward movement of the plungers while the carriage is in its forward position.

IRWIN KOTCHER.
